CLAIM

The ornamental design for a gaming machine with modular topper, as shown and described.

DESCRIPTION

FIG. 1 is a front perspective view of a gaming machine with modular topper showing our new design according to a first embodiment;

FIG. 2 is an exploded front perspective view thereof, with the modular topper shown separately for clarity of illustration;

FIG. 3 is a front elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front perspective view of a gaming machine with modular topper showing our new design according to a second embodiment;

FIG. 9 is an exploded front perspective view thereof, with the modular topper shown separately for clarity of illustration;

FIG. 10 is a front elevation view thereof;

FIG. 11 is a right side elevation view thereof;

FIG. 12 is a left side elevation view thereof;

FIG. 13 is a top plan view thereof;

FIG. 14 is a bottom plan view thereof;

FIG. 15 is a front perspective view of a gaming machine with modular topper showing our new design according to a third embodiment;

FIG. 16 is an exploded front perspective view thereof, with the modular topper shown separately for clarity of illustration;

(Continued)

FIG. 17 is a front elevation view thereof;
 FIG. 18 is a right side elevation view thereof;
 FIG. 19 is a left side elevation view thereof;
 FIG. 20 is a top plan view thereof;
 FIG. 21 is a bottom plan view thereof;
 FIG. 22 is a front perspective view of a gaming machine with modular topper showing our new design according to a fourth embodiment;
 FIG. 23 is an exploded front perspective view thereof, with the modular topper shown separately for clarity of illustration;
 FIG. 24 is a front elevation view thereof;
 FIG. 25 is a right side elevation view thereof;
 FIG. 26 is a left side elevation view thereof;
 FIG. 27 is a top plan view thereof; and,
 FIG. 28 is a bottom plan view thereof.
 The dashed broken lines in the figures illustrate portions of the gaming machine with modular topper that form no part of the claimed design.
